UNITED STATES PATENT OFFICE.

EDUARD SCHULTE, OF HAMM, WESTPHALIA, GERMANY, ASSIGNOR TO THE UNITED COKE AND GAS COMPANY, A CORPORATION OF WEST VIRGINIA.

FLUID-PRESSURE REGULATOR.

937,721.

Specification of Letters Patent. Patented Oct. 19, 1909.

Original application filed April 3, 1907, Serial No. 366,163. Divided and this application filed November 29, 1907, Serial No. 404,425.

To all whom it may concern:

Be it known that I, EDUARD SCHULTE, a subject of the Emperor of Germany, residing in Hamm i. W., Germany, have invented a certain new and useful Improvement 5 in Fluid-Pressure Regulators, of which the following is a specification.

This invention has relation to an improved form of electric reversing switch 10 adapted to operate by changes in fluid pressure, particularly for use in connection with automatically controlled blowing or suction machinery.

One principal object of this invention is 15 the provision of simple and effective mechanism whereby the results desired may be made operative by very small changes in fluid pressure; and in this connection, the preferred form of my invention is made 20 adjustable, not only for initially accommodating a given regulating device to a given air or gas pumping apparatus, but also for quickly compensating, from time to time, for minor changes in working conditions.

25 A preferred illustrative embodiment of this invention is shown in the accompanying drawings, wherein—

Figure 1 is a vertical central section of 30 my automatic governing switch; Fig. 2 is a plan view of the same and Fig. 3 shows a regulating system for a group of two blowers.

In Fig. 3 are shown two air or gas mains, 35 1 and 2, referred to herein as the supply main 1 and the delivery main 2. One or more blowers or pumps are employed in transferring the air or gas from the supply to the delivery main, and in Fig. 3, two of these are shown at 3 and 4. Each blower 40 is driven by an appropriate prime mover, as for instance, the steam engines 5 and 6, which transmit power by belts 7 and 8 or otherwise. The steam for driving these engines is supplied from the steam main 9 45 by pipes 10 and 11 leading to appropriate valves 12 and 13.

This invention is applicable to a system 50 wherein a separate electric motor is used for the governing device in each prime mover in the system, but in Fig. 3 I have shown the application of my invention to the use of a single electric motor or equivalent device so arranged as to simultaneously govern a plurality of prime movers. This system is

not limited to the use of two prime movers 55 and the shaft driven by the electric motor is broken off at the end of the figure to indicate indefinite length for connection to an indefinite number of prime movers.

In Fig. 3, the electric motor is shown at 60 14, and it is made to drive a shaft 15 supplied at proper intervals with worms 16 engaging worm wheels 17 (one for each prime mover). The shaft 18 of each worm wheel 65 operates one or the other of the valves 12, 13 in a well known manner, so that, when the shaft revolves in one direction it will slowly open the valves 12, 13, simultaneously, and it will close these valves when turned in the opposite direction. The electric motor 14 is 70 normally at rest and it is made to run in one direction or the other when required for regulation of the system, by means of the automatic governing switch shown in Figs. 1 and 2.

The mode of use of the governing switch 75 and its adjuncts will depend upon whether it is desired to regulate pressure in the supply main 1 or in the delivery main 2. If the pressure of the gas within the supply main 80 is to be regulated then the entrance pipe 19 shown in Figs. 1 and 2 must be connected to the supply main. If the pressure of the gas delivered is to be regulated, the pipe 19 must be connected to the delivery main. 85

The pipe 19 leads to the lower part 20 of a casing 21, the upper part of which is open to the atmosphere, as by the opening 22. The two parts of the space within the casing 21 are horizontally divided by a flexible or movable diaphragm preferably composed of a solid central disk 23 supported by a corrugated annular strip of flexible material, 24, such as thin leather.

Upon a standard 25, fixed to the top of the 90 casing 21 a balancing beam is supported, which beam is preferably composed of two light metal frames 26, 27 joined by insulating cross pieces 28 and supported upon the standard 25 by the knife edge 29.

The weight of the disk 23 is partly supported by the suspension bar 30 attached to the disk preferably at its center, which bar is provided at its upper end with a knife edge 31, resting upon an appropriate insulating cross piece 32 whose ends are fixed to the frames 26, 27.

Fig. 1 shows a balanced condition of the

governor, which is the position assumed when the pressure transmitted through the pipe 19 conforms to what is desired in the system to be regulated. In this position, assuming the pressure regulated to be less than the atmosphere, the combined weight of the suspension bar 30, of the flexible diaphragm and of the atmosphere on the one hand is balanced by the upward pressure of the gas in the chamber 20 and by the tipping effort of the balancing beams 26, 27. In any case a rough preliminary adjustment of the device is accomplished by sliding the weight 33 to the proper position on its arm and fixing the same once for all in that position by means of the binding screw 34. After this the smaller weight 35 can be moved along its arm to accomplish final adjustment where changed conditions in the system render it desirable. Notches are preferably provided with which the end of the screw 36 may engage. By these means the balancing of the apparatus is accomplished to suit any desired conditions so that the balancing beam remains horizontal when the gas pressure to be regulated is correct.

At each end of each frame 26, 27, a long metal contact is provided, the same being shown at 37, 38, 39 and 40, and each being preferably provided with a milled edge whereby its position may be adjusted by hand either by providing a thread on the pin for screwing it up and down or otherwise. Under each of these pins is placed a cup in which mercury is poured to such a level that the pins are not quite immersed, but stand a little above the liquid when the balancing beam is horizontal. These cups are shown at 41, 42, 43 and 44. Any conducting liquid may be used in these cups. Similar mercury cups 45, 46 are provided under the middle of such frame 26, 27 and a depending arm 47 (shown in dotted lines in Fig. 1) connects each frame permanently with the mercury in said cups. The wire 48 electrically connects the cup 43 with the cup 42, and the wire 49 connects 41 and 44. Wires 50, 51, connect two cups 45, 46 with the two armature brushes of the motor 14 as shown in Fig. 3. The terminals 52, 53 of the motor 14 are connected by the switch 54 to the electrical mains 55, 56. At 57 and 58 are shown the resistances ordinarily used in the armature and field magnet circuits of the motor.

From the description above given it will be obvious that, so long as the gas which enters the pipe 19 remains at the pressure desired and the pins on the balancing beam, do not touch the conducting liquid below them, the armature circuit of the motor 14 will not be closed, and there will be no change in the position of the valves 12 and

13. If, however, the pressure in the chamber 20 becomes excessive, the pins 38 and 40 will touch the liquid in the cups 42 and 44, 65 and circuit will be closed through one side of the switch 54 by cup 43, wire 48, cup 42, pin 38, frame 26, arm 47, cup 45, wire 50, through the armature, by wire 51, cup 46, arm 47, frame 27, pin 40, cup 44, wire 49, 70 cup 41 and resistance 57. This will drive the motor 14 in such a direction as to increase the opening of valves 12 and 13 and thus cause the blowers 3 and 4 to exert more exhausting action upon the supply main 1. If, on the contrary, the pressure in the chamber 20 becomes deficient, the circuit will be closed by the armature in the opposite direction and the action of the blowers will be decreased. 80

The above description conforms to the conditions existing when the apparatus shown in Figs. 1 and 2 is connected by pipe 19 to the supply main 1. It is, of course, obvious that, where the pipe 19 is connected to the delivery main 2, the electrical connections will be reversed. 85

The arrangement of balancing weights shown in Figs. 1 and 2 is that adopted when the normal pressure in the chamber 20 is 90 insufficient to support the weight of the diaphragm, the suspension bar and the atmosphere. It is obvious that suitable changes in the weights can be made for other normal conditions of interior gas pressure. 95

This is a division of another application of mine, Serial Number 366168 filed April 3rd 1907 wherein the general regulated blowing system herein shown is claimed.

What I claim is—

1. In combination with a closed chamber, a diaphragm therein and three pairs of cups containing conducting liquid all on said chamber; a balancing beam connected by knife-edge connection with said diaphragm, four conducting pins carried on opposite ends of said beam and adapted to dip into two of said pairs of cups and two conducting arms on opposite sides of the middle of said beam and dipping into the remaining 110 cups, substantially as described.

2. In apparatus of the class described, a horizontal diaphragm comprising a central plate with a flexible air tight border, a balancing beam composed of two mutually insulated side frames carried on a knife-edge between them and above said diaphragm plate and a depending pin at each end of each of said frames, substantially as described. 115
